(57) **CLAIM**

The ornamental design for game pieces, as shown and described.

DESCRIPTION

FIG. 1 is a perspective view of a game piece according to an embodiment of the present invention.

FIG. 2 is a top view of the game piece of FIG. 1.

FIG. 3 is a bottom view of the game piece of FIG. 1.

FIG. 4 is a right side view of the game piece of FIG. 1.

FIG. 5 is a left side view of the game piece of FIG. 1.

FIG. 6 is a front view of the game piece of FIG. 1.

FIG. 7 is a rear view of the game piece of FIG. 1.

FIG. 8 is a perspective view of a game piece according to an embodiment of the present invention where the shading indicates color contrast.

FIG. 9 is a top view of the game piece of FIG. 8.

FIG. 10 is a bottom view of the game piece of FIG. 8.

FIG. 11 is a right side view of the game piece of FIG. 8.

FIG. 12 is a left side view of the game piece of FIG. 8.

FIG. 13 is a front view of the game piece of FIG. 8.

FIG. 14 is a rear view of the game piece of FIG. 8.

The broken line showing of dots and rivets is included for the purpose of illustrating portions of the “article” and forms no part of the claimed design.
